UNITED STATES PATENT OFFICE.

WILHELM HEINRICH EYERMANN, OF WILMERSDORF, NEAR BERLIN, GERMANY.

SURFACE CONDENSER.

No. 890,417.

Specification of Letters Patent.

Patented June 9, 1908.

Application filed December 10, 1906. Serial No. 347,153.

To all whom it may concern:

Be it known that I, WILHELM HEINRICH EYERMANN, engineer, a subject of the German Emperor, residing at Wilmersdorf, near Berlin, Germany, have invented certain new and useful Improvements in Surface Condensers; and I do hereby declare the following to be a full, clear, and exact description of the invention, such as will enable others skilled in the art to which it appertains to make and use the same.

The present invention relates to surface condensers and an important object is to provide one in which steam is conducted at a high velocity to cooled concave curved surfaces, in order to bring about an intimate contacting of the steam with the cooled surface by means of the centrifugal force of the steam.

It is known that condensation of steam on cooled surfaces takes place more briskly, the more care is taken that the steam contacts directly with the surface with a brisk motion. This was hitherto obtained by obstructions causing the steam to whirl or eddy, *i. e.* imparting an irregular motion to it, for example by conducting the steam transversely through a bundle of condensing tubes, or by arranging projections running transversely to the direction of the steam at the cooling surfaces. These arrangements had the disadvantage that the velocity of the steam was very materially reduced by eddies, and the production of additional velocity for the continued motion of the steam which was not as yet condensed was combined with loss of pressure. The present invention avoids this disadvantage, as the steam flows regularly, and eddies which reduce the velocity

are avoided, without losing, however, the advantage of the intimate contact of the steam with the cooling surface. This effect is obtained by the steam being conducted at high speed to the regular concave curved cooling surfaces. The heavy particles of condensed water are thrown with great force against the concave surface by the centrifugal force which the steam develops, and are thus separated from the current of steam.

In order that the cooling surface may not become coated with a layer of water which would be detrimental to the working of the condenser, this water must be removed from

the cooling surface immediately after its separation from the steam. This is effected, 55 in accordance with the present invention, by cavities, holes, slots or the like being arranged at suitable places in the cooling surface, in such a manner that the separated water can just pass through, without the surface being so much interrupted, however, that the motion of the steam is disturbed in any considerable degree. The water which has passed through the said cavities is then conducted further away through pipes or 60 channels, so that it cannot get into the current of steam again.

In order to prevent having to specially produce the considerable velocity of steam which is necessary for a good effect, the cooling surfaces are preferably built as near as possible to the steam engine, especially when it is a steam turbine, which supplies the steam, so that the velocity of emission of the steam from said engine which in itself is unavoidable is employed for the purpose mentioned.

In order that the invention may be more clearly understood, reference is made to the accompanying drawing in which several embodiments are shown by way of example diagrammatically, and in which

Figure 1 is a vertical cross-section, and Fig. 2 is a longitudinal vertical section of one form, Fig. 3 is a longitudinal vertical section 85 of a steam turbine with another form of condenser directly attached thereto. Figs. 4, 5, 6, 7, and 8 show details of other forms. Fig. 9 is a longitudinal vertical section of still another form of condenser, and Fig. 10 90 is a partial section on the line 10—10 of Fig. 9.

Referring to Figs. 1 and 2, steam enters tangentially at *a* into the cylindrical drum *b* or condenser chamber, and in consequence 95 of its energy flows along a spiral path at the cooled cylinder surface *c* with only a slightly diminishing velocity. Slots *d* are situated in this surface, through which the separated water enters into the channels *e*, from which 100 it is conducted away through the pipe *f*. The cylinder is surrounded by a chamber *g* through which cold water flows. The water is admitted at *h* and discharged at *i*.

In Fig. 3 is shown the lower part of a turbine having another form of my invention

applied thereto. In this case the steam is supplied in a circular jet to the condenser. The cooling surfaces are stationary and may be regarded as generated by the rotation of the 5 semi-circular forms running from the top of the tube *k* horizontally outwards. The steam enters at *a* and then flows, as the arrow indicates, from without to within against the cooling surfaces *c* which are arranged one in and over another. The water 10 which is condensed enters into annular channels *e* through slots *d* at the edge of each ring, from which it flows away through the pipes *f* into the chamber *k*. The cold water chambers are situated above and below the cooling 15 surfaces *c*.

In order to increase the cooling surfaces without lengthening the path of the steam and without appreciably increasing the 20 resistance to its motion, ribs 1 (Figs. 4 and 5) may be arranged running in the direction of motion of the steam on the cooling surfaces. The slots and channels *d* and *e* may in this 25 case be preferably placed likewise in the direction of the flow of the steam.

The cooling surface may consist of a bundle of tubes according to Figs. 6, 7 and 8, which is formed in such a manner that it offers a concave surface which causes only 30 slight frictional resistance to the steam and the slots between the separate tubes allow the water which is condensed to pass through. The invention may also be employed as a preliminary condenser in combination with 35 an ordinary condenser.

In Figs. 9 and 10, still another form of condenser is shown, adapted to be applied to the lower end of a vertically arranged turbine. The steam enters at *a* in the form of an annular 40 jet and passes inwardly over the tubes *c* which are separated from each other by spaces *d*. The tubes *c* are hollow, as shown at *g*. The inner ends of the tube communicate with an annular portion *p*, which is connected by a pipe *m* with the cold water supply, and the outer ends of the tubes are connected to an annular casing, having a discharge outlet *o*. The condensed water 45 passes down through the spaces *d* between the tubes *c* and is discharged through the outlet opening *q*.

What I claim as my invention and desire to secure by Letters Patent is:—

1. The combination of a condenser chamber having an opening for the admission of steam and an emission opening, with water-cooling means adjacent to the same, the side of said chamber being concave in the direction of the flow of the steam in the same, and 50 having cavities or slots in the same, and conduits communicating with said slots, whereby the centrifugal force of the steam entering said chamber causes the steam to intimately

contact with the cooling surface of said chamber, and the condensed water is removed 65 through said conduits.

2. The combination of a condenser chamber comprising a plurality of annular tubes having an opening for the admission of steam and an emission opening, with water-cooling 70 means adjacent to the same, the side of said chamber being concave in the direction of the flow of the steam in the same, whereby the centrifugal force of the steam entering said chamber causes the steam to intimately 75 contact with the cooling surface of said chamber.

3. The combination of a condenser chamber comprising a plurality of annular tubes having an opening for the admission of steam 80 and an emission opening, with water-cooling means adjacent to the same, the side of said chamber being concave in the direction of the flow of the steam in the same and having cavities or slots in the same, and conduits 85 communicating with said slots, whereby the centrifugal force of the steam entering said chamber causes the steam to intimately contact with the cooling surface of said chamber, and the condensed water is removed 90 through said conduits.

4. The combination of a condenser chamber comprising a plurality of annular tubes having an opening for the admission of steam and an emission opening, with water-cooling 95 means adjacent to the same, the side of said chamber being concave in the direction of the flow of the steam in the same and provided with ribs parallel to the direction of flow of the steam, whereby the condensing 100 surface is increased.

5. The combination of a condenser chamber comprising a plurality of annular concentric tubes closely adjoining one another and provided with water-separating slots and 105 channels arranged concentrically therewith, said tubes being provided with steam admission and emission openings and conduits communicating with the latter, with water-cooling means adjacent to the same, substantially 110 as described.

6. The combination of a steam engine having an exhaust port with a condenser chamber having an admission opening in immediate proximity to said exhaust port and an 115 emission opening, a pipe connecting said admission opening with said exhaust port, and water-cooling means adjacent to said chamber, the side of said chamber being concave in the direction of the flow of the steam in 120 the same, for the purpose specified.

7. In combination, a steam engine having an exhaust port, a condenser chamber having an admission and an emission opening, water-cooling means adjacent to said chamber, the 125 side of said chamber being concave in the di-

rection of the flow of the steam in the same, a steam conduit connecting said exhaust port with said admission opening of said chamber, a surface condenser having an admission opening, and a steam conduit connecting the latter opening with the emission opening of said condenser chamber.

In testimony whereof, I affix my signature, in presence of two witnesses.
